(57) **CLAIM**

The ornamental design for overhead soffit, as shown and described.

DESCRIPTION

FIG. 1 is a perspective view of a first embodiment of an overhead soffit showing our new design;

FIG. 2 is a left side elevational view thereof;

FIG. 3 is a right side elevational view thereof;

FIG. 4 is a front side elevational view thereof;

FIG. 5 is a rear side elevational view thereof;

FIG. 6 is a bottom plan view thereof;

FIG. 7 is a perspective view of a second embodiment of an overhead soffit showing our new design;

FIG. 8 is a left elevational view thereof;

FIG. 9 is a right elevational view thereof;

FIG. 10 is a front side plan view thereof;

FIG. 11 is a rear plan view thereof; and,

FIG. 12 is a bottom plan view thereof.

The broken line showing is for illustrative purposes only and forms no part of the claimed design.
